ADJUSTABLE DRAWING FRAME

Bryant W. Gossett and Walter Casbin Lineberger, Gastonia, N. C., assignors to Bryant W. Gossett, Gastonia, N. C.

Application October 5, 1940, Serial No. 359,850

11 Claims. (Cl. 19—130)

This invention relates to textile fiber preparation machinery and more especially to an improved drawing frame, which is employed for the parallelization of the fibers. Specifically the invention comprises a draw frame having means for varying the distances between the sets of draft rolls in combination with an adjustably mounted drive for a stop motion.

In the manufacture of rayon, acetate, and cotton yarns, the material is delivered to the mill in bales. Subsequent to delivery, the material is passed through bale breakers, openers, and the like to remove impurities therefrom and then it is run through pickers to form laps. These laps are carded and condensed into slivers. In order to further even the product and to parallelize the fibers, several of these strands are simultaneously passed through sets of drawing rolls, such as shown in the accompanying drawings, and these strands emerge from the drawing rolls in a single strand which is usually about the same size as one of the several strands which enter. Due to the fact that the speed of the sets of rolls progressively increases from the back set to the front set, there is a resultant draft in the fibers which serves to parallelize them. From the final drawing process, this strand is run through fly frames and spinning frames which serve to reduce the count of the yarn and to supply the necessary twist.

During recent years, the mills have been using much rayon fiber having a staple length of two inches or more. As is well known, cotton has a staple length of $\frac{3}{4}$ " to approximately $1\frac{1}{2}$ ". Since the distance between the sets of drawing rolls are usually determined by the length of staple, it is seen that a problem is encountered in adapting the old cotton drafting frames for drafting long staple rayon fiber. Not only is it necessary to provide a new means for varying the distance between the sets of rolls, but it is also necessary to adapt this new mechanism to the drawing frame stop motion so that its operation will not be adversely affected.

It is, therefore, an object of this invention to provide a drawing frame having a plurality of interconnected adjustable sets of drafting rolls and a stop motion therefor, in combination with a train of adjustable gears for driving the rolls and a second train of adjustable gears driven by the first train for driving the stop motion. Of course, there is an adjustable connection between the stop motion and the second train of gears. In other words, the two trains of gears are connected in series. Since they are adjust-

ably mounted, the overall length of the two trains can be easily varied to suit the distances between the rolls without disturbing the operation of the stop motion.

5 Some of the objects of the invention having been stated, other objects will appear as the description proceeds, when taken in connection with the accompanying drawings, in which—

Figure 1 is a plan view of the two ends of a drawing frame, the central portion thereof being broken away, showing the present invention embodied therein;

Figure 2 is a vertical transverse sectional view taken along the line 2—2 in Figure 1;

15 Figure 3 is a vertical transverse sectional view taken along the line 3—3 in Figure 1;

Figure 4 is a vertical transverse sectional view taken along the line 4—4 in Figure 1;

Figure 5 is an end elevation looking along the line 5—5 in Figure 1;

Figure 6 is an isometric view, with certain portions thereof broken away and other portions omitted, showing the stop motion mechanism employed in the draw frame;

25 Figure 7 is a sectional view similar to the right-hand portion of Figure 3, but showing the position of the stop motion lever as it appears when it is in operation;

Figure 8 is a sectional detail view taken along the line 8—8 in Figure 1;

30 Figure 9 is a sectional detail view taken along the line 9—9 in Figure 1.

Referring more specifically to the drawings, the numerals 10 and 11 denote the end frames 35 of a drawing mechanism which are secured together by means of a longitudinally disposed supporting member 12. Member 12 has a flat upper surface which serves as a support for roll stand brackets 14, 15, and 16, each of said brackets

40 having a slot 17 disposed therein in which bolts 18 are adapted to be adjustably mounted. Each of the bolts have their upper ends threadably secured in blocks or roll stands which support sets of drafting rolls. For example, there are four bottom drafting rolls, namely 20, 21, 22 and 23 which are supported by roll stands 24, 26, 26 and 27, respectively. Each of these stands is secured in adjusted position on its respective bracket by means of a stud bolt 18. When it is desired to vary the distance between the above-named stands, it is only necessary to loosen the stud bolts 18 and then move the stands and the associated rolls to the desired position and then again tighten the bolts. Bottom rolls 20, 21, 22 and 23 have top rolls 30, 31, 32 and 33, respec-

45

50

55

tively mounted thereabove, said top rolls likewise being supported by the stands 24 to 27, respectively.

During the operation of the draw frame, a plurality of slivers 36, 37, 38, 39, 40 and 41 are fed into the draw frame over spoons 42, and then between rolls 23 and 33, rolls 22 and 32, rolls 21 and 31, and rolls 20 and 30 to effect the necessary drafting operation on the respective strands. The slivers are then condensed into a single strand 44, which passes downwardly through eyelet 45 and between rollers 46 and 47, from whence it is deposited into a suitable container not shown.

Each of the spoons 42 is pivoted intermediate its ends upon a longitudinally disposed bar 50 (Figures 1 and 4) which bar is supported beneath an apron member 51, said apron in turn, being supported by the brackets 14, 15, and 16. The lower end of each spoon has a hooked portion 52, the lower end of which is normally held in elevated position by the tension and weight of the strand on its upper end, as shown in Figure 4. In this position, the upper end of lever arm 56 will clear the hook end 52 as it oscillates back and forth thereunder, along with shaft 51. Upon the breakage of a sliver which is supported by the upper end of the spoon, the hooked portion 52 will drop into the path of arm 56 and thereby cause the stop motion to be actuated in a manner to be hereinafter described.

The rollers 46 and 47 have gears 59 and 60, respectively on each end thereof, which mesh with each other. The ends of the rollers 46 and 47 are journaled in the brackets 14 and 16. Roller 47 has a shaft 47a extending therefrom upon which a gear 62 is fixedly secured and this gear is driven from front bottom roll drive shaft 63 through the medium of gears 64, 65, 66, 67 and 68. Gear 68 is fixedly secured on drive shaft 63, said drive shaft being a continuation of the front bottom roll 20.

The end of drive shaft 63 is journaled in bearing 69 which in turn is supported by end frame 10. A fixed pulley 70 is mounted on the shaft 63 and upon the pulley a belt 71 is adapted to be mounted during normal operation. Also a loose or idler pulley 72 is mounted on shaft 63 alongside pulley 70. This idler pulley is adapted to receive the belt 71 when it is desired to stop the machine.

As heretofore stated, the drive shaft 63 is connected to the bottom front roll 20 which extends longitudinally of the drawing frame. At a point beyond the bracket 16 (see Figure 1) the end of bottom roll 20 has a pinion 75 mounted thereon, said pinion meshing with a pinion 76. The pinion 76 has integral therewith a smaller pinion 77 and both of these pinions 76 and 77 are rotatably mounted upon a stud 78 (see Figure 5). Pinion 77 meshes with a pinion 79 on the end of bottom roll 21.

When the distance between the bottom rolls 20 and 21 is varied, it is necessary to adjust the position of the intermediate gears or pinions 76 and 77, to cause them to properly mesh. This adjustment is partially effected by means of a horizontal slot 80 in the upper end of a plate 81, said plate 81 having a slot 82 near the lower end thereof which is penetrated by a bolt 83. Bolt 83 is secured to a bracket 84 rising from the supporting member 12. By virtue of the slot 80, the gears 76 and 77 can be adjusted horizontally and by means of the slot 82 these same gears can be adjusted vertically, thereby insuring that pin-

ions 76 and 77 will mesh with their respective gears.

By referring to Figures 1 and 2, it is seen that a bracket 90 is supported by the table member 12. The upstanding leg of this bracket cantilevers to the left of this table member for supporting the end of shaft 47a and also for supporting the gears 64, 65, 66 and 67. The top edge of the upstanding leg of bracket 90 has a notch 91 therein for accommodating a suitable bearing 92 which, in turn, supports the shaft 63 previously described. Around the shaft 63 and disposed adjacent one face of the upstanding leg of bracket 90 is a plate 95, said plate having an arcuate slot 94 therein which is penetrated by a bolt 97. Bolt 97 also penetrates the upstanding leg of bracket 90. Since this slot is arcuate and has its center about the shaft 63, it is seen that the plate 95 can be rotated about the shaft 63 within the limits of the length of the slot.

The upper end of the plate 95 has a notch 99 cut therein for the reception of a stud 100. This stud has gears 101 and 102 rotatably mounted thereon, both of said gears being adapted to rotate in unison. Gear 101 is driven by a gear 104 which is fixedly secured around shaft 63. The gear 102 meshes with a gear 106 which gear also meshes with another gear 107, both the gears 106 and 107 being rotatably mounted upon plate 111, said plate being pivoted as at 112 to the upstanding leg of a bracket 108. The lower edge of plate 111 has an arcuate slot 113 therein whose center is pivot point 112. This slot is penetrated by stud bolt 115, and the end of the bolt is adapted to threadably penetrate one of the interiorly threaded holes 115a in the upstanding leg of bracket 108. By so mounting the gears 106 and 107, the positions can be changed to suit various settings of the drafting rolls. Bracket 108 has a slot 109 in the outstanding leg thereof, which rests upon the top of table member 12. Slot 109 is penetrated by stud bolts 110, which bolts are loosened when it is desired to adjust the position of the bracket 108 and its associated gears 106 and 107 on the table 12.

The back roll 23 has a gear 114 fixedly secured on the end thereof, which is driven by the gear 107. The back roll 23 extends the length of the frame as shown in Figures 1 and 5, and has a gear 116 mounted thereon, said gear 116 meshing with a gear 117, which gear 117 forms an integral part of another gear 118. Both of the gears 117 and 118 are rotatably mounted upon a stud 119. The gear 118 also meshes with a pinion 120 on the end of bottom roll 22.

When the position of the bottom rolls 22 and 23 is changed, it is necessary to vary the positions of the gears 117 and 118 to cause these gears to properly mesh with the respective pinions on the ends of the rolls. In order to provide this adjustment, a suitable horizontal slot 125 is provided in the upper end of a plate member 126, said plate member also having a vertically disposed slot 127 therein which is penetrated by a bolt 128. This bolt also penetrates bracket 84. By virtue of the slot 125 the gears 117 and 118 may be moved horizontally and by virtue of the slot 127 the necessary vertical movement of gears 117 and 118 can be effected. Of course, it is necessary to also adjust the position of gears 101, 102, 106 and 107 at the other end of the draw frame when the distance is varied between the bottom rolls 22 and 23. By rotating the

plate 95 and its associated gears 101 and 102 about the shaft 63, and by adjusting the position of the bracket 108 and its associated gears 106 and 107, through the medium of slot 109 and 113, this last-named adjustment can be effected (see Figure 6).

When the distances between the sets of rolls are varied it is also necessary to make adjustments to insure that the stop motion will be properly driven. In other words, when the back roll 23 has its position changed, the associated gear 114 will likewise have its position changed, and consequently, the geared connection between gear 114 and the stop motion must be adjusted accordingly.

The gear 114 is adapted to mesh with a gear 130, said gear meshing with a smaller gear 131. Both of these gears 130 and 131 are rotatably mounted upon a plate 132 which in turn, is secured to bracket 14 (see Figure 8) by any suitable means such as bolt 133. The downstanding leg of bracket 14 has a longitudinally disposed slot 135 therein for the accommodation of the bolt 133 and also to permit the adjustment of the plate 132 longitudinally thereof. Also the downstanding leg of bracket 14 has a groove 136 which accommodates a projection 132a on the plate 132. This projection permits the plate 132 to be held in position relative to the bracket 14 by using only one bolt 133. It is therefore seen that the gears 130 and 131 can be moved longitudinally of the bracket to conform to the adjustment made of the train of gears 101, 102, 106, 107 and 114 which drives the back bottom rollers 22 and 23.

The gear 131 has a pin 140 extending from one face thereof which penetrates a slot 141 in a lever 142, said lever being pivoted as at 143 to a short arm 144. This short arm is fixed on shaft 145, which shaft has its end rotatably mounted on bracket 146, said bracket being secured to the downstanding leg of table member 12. Since the arm 144 is fixedly secured upon the shaft 145, this shaft will oscillate back and forth during the rotation of the gear 131. By referring to Figures 4 and 6, it is seen that the shaft 145 has an upstanding lever 148 fixedly secured thereon. The upper end of this lever has a horizontal link 149 secured thereto, which link has its other end secured to the upper end of another lever 150 and the lower end of lever 150 is fixedly secured on previously described shaft 57. As heretofore stated, shaft 57 has fixed thereon an arm 56, the upper end of which oscillates back and forth beneath the hooked portion 52 of spoon 42 when the drawing frame is in operation.

By observing Figures 2, 3, 6 and 7, it will be noted that the lower end of the stop motion lever 142 has an arcuate projection 155 which partially encircles the shaft 145. A counterweight 157 is pivoted as at 158 to the bracket 146. The weight 157 has an upwardly projecting portion 156a which passes on the far side of the arcuate portion 155 as seen in Figures 6 and 7. This portion 156a has a lateral projection 156 which projects toward the observer in Figures 6 and 7, and thus the weight of member 157 holds members 142 and 144 in aligned position as long as shaft 145 is allowed to oscillate. This counterweight has an upstanding leg 159 which is adapted to rest in notch 160 in sleeve 161, said sleeve being mounted upon a shaft 162, which, in turn, is slidably mounted in bracket

163. The sleeve 161 is slidably mounted in bracket 146.

The end of the sleeve 161 and the end of shaft 162 nearest the observer have fixedly secured thereon a forked arm 165, said fork being adapted to encircle the belt 71. A compression spring 166 is mounted around the shaft 162 and between the bracket 163 and sleeve 161. This compression spring normally tends to force the notch 160 into engagement with the upper end of upstanding arm 159. In the position shown in Figure 6, the belt 71 is mounted on the fixed pulley 70, but upon the breakage of one of the strands 36 to 41 inclusive, the hooked portion 52 on the lower end of spoon 42 will drop downwardly into the path of the upper end of oscillating arm 56. This will prevent the oscillation of the arm 56, but since it is positively driven through the medium of gears 101, 102, 106, 107, 114, 130 and 131, pin 140, lever 142, arm 144, shaft 145, lever 148, link 149, lever 150 and shaft 57, there must be some flexible member which will yield or give way to prevent breakage of the parts. This yielding is effected around pivot point 143 between the arm 144 and lever 142. In other words, the portion 144 remains stationary when the arm 56 engages hook 52, but the lever 142 is caused to rotate about pivot point 143 to the position shown in Figure 7. This movement will raise the arcuate portion 155 and thereby cause the projection 156 and the counterweight 157 to be raised. Upon the raising of the counterweight, the vertical arm 159 will be moved out of the notch 160 to thereby allow the compression spring 166 to move the shaft 162 and forked portion 165 toward the observer in Figures 1 and 6 to cause the belt 71 to be shifted from the fixed pulley 70 to the loose pulley 72 and thereby stop the machine.

40 The sleeve 161 has integral therewith a lever 170 which extends radially therefrom and has a slot 171 therein, said slot encircling the shaft 145. This lever prevents rotation of the sleeve 161 and the shaft 162 and thereby holds the notch 160 in its proper position for the reception of the upstanding arm 159.

45 The purpose of the slot 141 in the stop motion lever 142 is to permit the movement of gears 130 and 131 longitudinally of the supporting bracket 14.

50 It is therefore seen that in the present embodiment of the invention there is disclosed means whereby a substantial amount of adjustment of the distances between the sets of drawing rolls can be effected by adjusting interconnecting driving gears therefor. Also this adjustment can be made without affecting adversely the operation of the stop motion mechanism since the slot 141 permits the driving train of gears for the stop motion lever to occupy various positions relative thereto.

55 In the drawings and specification there has been set forth a preferred embodiment of the invention and although specific terms are employed, they are used in a generic and descriptive sense only and not for purposes of limitation, the scope of the invention being set forth in the appended claims.

We claim:

70 1. In a drawing frame for slivers and the like, having a plurality of sets of drafting rolls between which the strands pass with means for varying the distance between said sets of rolls and having also a train of interconnecting gears for driving said rolls, means for adjusting the

position of the rolls to vary the distance there-between, means for individually adjusting the position of some of the gears to cause the length of the train to conform to the adjustment between the sets of rolls, a stop motion lever and a second train of adjustably mounted gears driven by said first train, said second train also being adjustably mounted for movement relative to the stop motion lever, said lever having a sliding connection with said second train of gears whereby said second train of gears can be moved relative to said lever when the length of the first train of gears is varied, while maintaining connection between the stop motion lever and the second train of gears.

2. In a drawing frame for slivers and the like having a plurality of sets of drafting rolls between which the slivers pass with means for varying the distance between said sets of rolls, a train of gears for driving said rolls, means for varying the overall horizontal distance between the end gears of the train, a stop motion lever operable by said train of gears, and an adjustable connection between said lever and said train of gears whereby the distance between the lever and the gears can be varied, without disrupting the connection between the train of gears and said lever.

3. In a drawing frame for fibers having a plurality of sets of drawing rolls, each set comprising a top and bottom drawing roll, said bottom rolls being geared together for rotation and said frame having means for adjusting the distance between the sets of drawing rolls, a stop motion mechanism, a geared connection between the rear bottom drawing roll and the stop motion mechanism, and means movably mounting the last-named geared connection relative to the stop motion, and means for maintaining the connection between the stop motion mechanism and the geared connection when the two are moved relative to each other.

4. In a drawing frame for fibers having a plurality of sets of drawing rolls, each set comprising a top and bottom drawing roll, said bottom rolls being geared together for rotation and said frame having means for adjusting the distance between the sets of drawing rolls, a stop motion mechanism, a geared connection between the rear bottom drawing roll and the stop motion mechanism, means for slidably mounting the last-named geared connection relative to the stop motion, and means for maintaining the connection between the stop motion mechanism and the geared connection when the two are moved relative to each other.

5. In a drawing frame for fibers having a plurality of sets of drawing rolls, each set comprising top and bottom drawing rolls, said bottom rolls being geared together for rotation and said frame having means for adjusting the distance between the sets of drawing rolls, a stop motion mechanism, a geared connection between the rear bottom drawing roll and the stop motion mechanism, means movably mounting the last-named geared connection relative to the stop motion, said stop motion mechanism including a member having an extended slot therein and one of the gears in the last-named connection between the rear bottom drawing roll and the stop motion mechanism having a pin therein penetrating said elongated slot; whereby when said last-named geared connection is moved to follow the adjustment of the position of the drawing rolls, the pin will remain in said

slot to operate the stop motion mechanism regardless of the position of the drawing rolls.

6. In a drawing frame for fibers having a plurality of sets of drawing rolls, each set comprising top and bottom drawing rolls, said bottom rolls being geared together for rotation and said frame having means for adjusting the distance between the sets of drawing rolls, a stop motion mechanism, a geared connection between the rear bottom drawing roll and the stop motion mechanism, means for slidably mounting the last-named geared connection relative to the stop motion, said stop motion mechanism including a member having an extended slot therein and one of the gears in the last-named geared connection between the rear bottom drawing roll and the stop motion mechanism having a pin therein penetrating said elongated slot, whereby when said last-named geared connection is moved to follow the adjustment of the position of the rolls, the pin will remain in said slot to operate the stop motion mechanism regardless of the position of the drawing rolls.

7. In a drawing frame for fibers having a plurality of sets of drawing rolls, each set comprising top and bottom drawing rolls, said bottom rolls being geared together for rotation and said frame having means for adjusting the distance between the sets of drawing rolls, the driving connection between all of the bottom rolls being adjustable as to position to maintain driving contact between all of the rolls, regardless of distances apart to which they are adjusted, a stop motion mechanism, a geared connection between the rear bottom drawing roll and the stop motion mechanism, means movably mounting the last-named geared connection relative to the stop motion, and means for maintaining the connection between the stop motion mechanism and the last named geared connection when the two are moved relative to each other.

8. In a drawing frame for fibers having a plurality of sets of drawing rolls, each set comprising top and bottom drawing rolls, said bottom rolls being geared together for rotation and said frame having means for adjusting the distance between the sets of drawing rolls, the driving connection between all of the bottom rolls being adjustable as to position to maintain driving contact between all of the rolls, regardless of distances apart to which they are adjusted, a stop motion mechanism, a geared connection between the rear bottom drawing rolls and the stop motion mechanism, and means slidably mounting the last-named geared connection relative to the stop motion, and means for maintaining the connection between the stop motion mechanism and the last named geared connection when the two are moved relative to each other.

9. In a drawing frame for fibers having a plurality of sets of drawing rolls, each set comprising top and bottom drawing rolls, said bottom rolls being geared together for rotation and said frame having means for adjusting the distance between the sets of drawing rolls, the driving connection between all of the bottom rolls being adjustable as to position to maintain driving contact between all of the rolls regardless of distances apart to which they are adjusted, a stop motion mechanism, a geared connection between the rear bottom drawing roll and the stop motion mechanism, means movably mounting the last-named geared connection rel-

ative to the stop motion, said stop motion mechanism including a member having an extended slot therein and one of the gears in the last-named connection between the rear bottom drawing roll and the stop motion mechanism having a pin therein penetrating said elongated slot, whereby when said last-named geared connection is moved to follow the adjustment of the position of the drawing rolls, the pin will remain in said slot to operate the stop motion mechanism, regardless of the position of the drawing rolls.

10. In a drawing frame for fibers having a plurality of sets of drawing rolls, each set comprising top and bottom drawing roll, said bottom rolls being geared together for rotation and said frame having means for adjusting the distance between the sets of drawing rolls, the driving connection between all of the bottom rolls being adjustable as to position to maintain driving contact between all of the rolls regardless of distances apart to which they are adjusted, a stop motion mechanism, a geared connection between the rear bottom drawing roll and the stop motion mechanism, means for slidably mounting the last-named geared connection relative to the stop motion, said stop motion mechanism including a member having an extended slot therein and one of the gears in the last-named geared connection between the rear bottom drawing roll and the stop motion mechanism having a pin therein penetrating said elongated slot, whereby when said last-named geared connection is moved to follow the adjustment of the position of the rolls, the pin 35 will remain in said slot to operate the stop motion mechanism, regardless of the position of the drawing rolls.

11. In a drawing frame for slivers and the like, comprising a stationary front bottom roll, a second bottom roll disposed rearwardly and adjacent the front roll and being adjustably mounted relative to the first roll, an adjustably geared connection between said rolls whereby a driving connection can be maintained when the distance between the rolls is varied, a third bottom roll adjustably disposed rearwardly and adjacent the second roll, a fourth bottom roll disposed rearwardly and adjacent the third bottom roll, a second adjustable geared connection between said third and fourth bottom rolls, whereby a driving connection can be maintained when the distance between the third and fourth rolls is varied, a top roll for each of said bottom rolls, an adjustable geared connection between said rear bottom roll and said front bottom roll to permit a driving connection to be maintained when the distance between the front and fourth rolls is varied, a stop motion shaft mounted for oscillation on said frame, a slotted lever secured to said shaft, an adjustable train of gears driven by said adjustable geared connection between the front and rear rolls, an eccentrically located pin projecting from the face of one of the gears in the train, said pin normally penetrating said slot in the stop motion lever, whereby when the gears rotate the eccentric pin will cause the stop motion lever to oscillate and whereby a driving connection will be maintained when the positions of the adjustable train of gears is changed relative to the lever.

BRYANT W. GOSSETT.

WALTER CASBIN LINEBERGER.
